(57) **CLAIM**

The ornamental design for a cat exercise wheel, as shown and described.

DESCRIPTION

FIG. 1 is a front, right, top perspective view of a cat exercise wheel, showing my new design;

FIG. 2 is a rear, left, bottom perspective view thereof;

FIG. 3 is a front elevational view of the enlarged scale thereof;

FIG. 4 is a rear elevational view of the enlarged scale thereof;

FIG. 5 is a left side view of the enlarged scale thereof;

FIG. 6 is a right side view of the enlarged scale thereof;

FIG. 7 is a top plan view of the enlarged scale thereof;

FIG. 8 is a bottom plan view of the enlarged scale thereof;

FIG. 9 is an enlarged view of detail 9 in FIG. 5;

FIG. 10 is an enlarged view of detail 10 in FIG. 6; and,

FIG. 11 is an enlarged view of detail 11 in FIG. 7.

The dashed broken lines in the figures are for the purposes of illustrating portions of the cat exercise wheel and form no part of the claimed design.

The short-short-long dashed broken lines immediately adjacent to the claimed areas in the views represent the boundaries of the design and form no part of the claimed design. The dash-dot-dash broken lines are for notating enlarged views and form no part of the claimed design.
